STACY RISLER, OF LOCKTOWN, NEW JERSEY.

Letters Patent No. 97,815, dated December 14, 1869.

IMPROVEMENT IN CHURNS.

The Schedule referred to in these Letters Patent and making part of the same.

To all whom it may concern:

Be it known that I, STACY RISLER, of Locktown, in the county of Hunterdon, and State of New Jersey, have invented a new and useful Improvement in Churns; and I do hereby declare that the following is a full, clear, and exact description of the construction and operation of the same, reference being had to the accompanying drawings, making a part of this specification, in which—

Figure 1 is a longitudinal section, taken in the plane xx of fig. 2.

Figure 2 is a horizontal section, taken in the plane yy of fig. 1.

Like letters in both figures of the drawings indicate like parts.

My invention relates to the class of churning whose dashers have a swinging or oscillating motion within an elongated box; and the object of it is to simplify and economize the cost of construction of such a churn, and yet enable it to perform the work thoroughly, and consume but little time in the performance of it; also, to so constructing and arranging the several parts connecting with, and supporting the arm of the dasher, as that they may be readily detached from one another, and from the body of the churn, so that the latter may be more conveniently stowed away when not in use.

I construct and operate my invention as follows:

A is an elongated box, with a curved bottom to suit the curve the dasher would make when oscillating, and having the ends inclined inwardly; the end-pieces $a a$ being let in a little from the sides, top, and bottom, and having cleats $b b$ nailed or screwed up and down thereon, about the centre thereof, which cleats, in connection with the edges of the top pieces, are so constructed as to form dovetails on the ends of the box, to receive the standards $B B$, which fit loosely but snugly therein.

The upper edges of the sides of the box incline a short distance at right angles from the ends thereof, and then terminate horizontally to receive the lids or cover $c c$, one being on each side of the arm C of the dasher, the ends of which lids are recessed or rabbeted on the under side, to fit and rest on corresponding recesses or rabbets on the upper side of the top pieces.

The lids have thumb-notches on the under-side edges, so that they may be removed by placing the thumb thereunder when putting the cream or milk in the churn, or when removing the butter from the same.

The standards have openings let into them from the tops thereof, to receive the ends of the cross-bar D , which fit snugly therein, and are secured thereto by removable pins.

An opening is made edgewise through the centre of

the cross-bar, to receive the end of the arm of the dasher, which arm is secured thereto by a removable pin, the opening being large enough to allow free play to the arm.

The standards project up to a height sufficient to give the dasher the proper swinging motion.

The arm, from the dasher E to just above the lids, is made as narrow as the strength of the arm will permit, so as to allow the lids to come as close together as possible around the arm, in order to avoid any liability of the milk or butter spattering out from the top of the churn.

The dasher is attached firmly to the bottom end of the arm, and consists of a head provided with a suitable number of diamond-shaped blades d , the head being rounded on the under side, from edge to edge, so as to have the edges thereof sharp enough to cut through the butter or cream, and thus work easier. The shape of the blades enables them to cut the little cells or globules containing the butter, and otherwise so agitate the cream or milk, by jamming or dash-ing the same between the inwardly-inclined sides of the blades, as to work up and get all the butter from the milk or cream, in a thorough manner, without wastage, as is common with many churning, from the fact of the dashers failing to expel or work out all the butter.

The dasher fits loosely but snugly within the box, and oscillates from its axis above, and occupies sufficient room, in respect to the depth of the box, as to prevent the milk or butter from working over the top of the dasher when swung out fully, thus giving the cream or butter the full benefit of the stroke or dash of the blades.

The buttermilk is withdrawn from a hole in the side of the box or churn, it being stopped up by a plug.

Operation.

A pin, e , is put through the arm, a little above the lids, which pin, by slipping the end of the lever F over it, (the lever having a hole near the end to fit it,) will enable the churn or the dasher to be operated or oscillated, either by drawing the lever back and forth from the end of the churn or box, or the operator may sit in a chair alongside thereof, and work the dasher more conveniently by removing the lever and taking hold of the pin with the hand, as may be deemed most convenient; the churn being supported on legs of a suitable height to admit of its being done in a sitting position.

The standards, by their inclining forward, and fitting in the dovetailed ends of the box, form steady-braces for the support of the cross-bar, and at any time when desired to place the churn out of the way as much as possible, all that is necessary to do is to re-

move the pins holding the several parts together, and withdrawing the standards from the dovetails, when the churn will be reduced in size so as not to occupy as much space as before.

I do not claim a swinging dasher, for I am aware of the same being in the patent of A. J. Pope, December 4, 1866; but

What I do claim, and desire to secure by Letters Patent, is—

The dasher-head **E**, diamond-shaped blades **d**, arm **C**, removable bar **D**, and removable standards **B** **B**, in

combination with dovetailed ends **b** of box **A**, provided with removable lids **c**, the arm of dasher being operated either by pin **e** or removable lever **F**, constructed and arranged substantially as described.

As evidence that I claim the foregoing as my invention, I have hereunto set my hand, in the presence of two witnesses.

STACY RISLER.
